UNITED STATES PATENT OFFICE.

RALPH E. BATES, OF PHILADELPHIA, PENNSYLVANIA, ASSIGNOR TO JOHN NAZEL, OF PHILADELPHIA, PENNSYLVANIA.

MECHANISM FOR APPLYING FLEXIBLE STRIPS.

1,132,901.

Specification of Letters Patent. Patented Mar. 23, 1915.

Application filed August 13, 1912. Serial No. 714,764.

To all whom it may concern:

Be it known that I, RALPH E. BATES, a citizen of the United States, residing in the city of Philadelphia, county of Philadelphia, and State of Pennsylvania, have invented an Improved Mechanism for Applying Flexible Strips, of which the following is a specification.

This invention is designed for applying strips of material to articles, particularly strips of tape to blanks to form hinged joints or provide reinforcements in the manufacture of cartons, backings for pamphlets and the like, which strips are by my improvements carried to position for application by pneumatic suction means.

In the preferred embodiment of my invention there is employed a machine comprising means by which a strip of tape is drawn into position to be cut to a desired length by automatic means and carried to a device, suitably a wheel, on which it is held by suction and by which it is carried to position for application to a blank, which may be conveniently positioned for receiving the strip by a traveling conveyer.

The characteristics of my invention are set out in the following description and the accompanying drawings in illustration thereof.

In the drawings, Figure 1 is a top plan view of a machine embodying the preferred application of my improvements; Fig. 2 is a side elevation thereof; Fig. 2^A is a transverse sectional view of the table shown in Fig. 2 on the line A—A thereof; Fig. 2^B is an end elevation of the tape cutting mechanism on the line B—B of Fig. 2; Fig. 3 is an elevation of the machine from the side opposite that shown in Fig. 2; Fig. 4 is an end elevation thereof; Fig. 5 is a top plan view, part sectional, of the tape cutting mechanism; Fig. 6 is a diametrical sectional view of the frame of the tape gripping mechanism and the suction wheel by which the tape is applied to the blank; Fig. 7 is an elevation, part sectional, showing the tape cutting, gripping and applying mechanism; Fig. 8 is a detail showing the cam mechanism by which the tape cutting mechanism is operated; Fig. 9 is a diagrammatic view illustrating how the tape is drawn through the machine and over the suction wheel; and Fig. 10 is a perspective

view of a blank having a strip applied thereto.

In the drawings is shown a table comprising longitudinal I-beams 1 supported by legs 2 laterally braced by struts 3, cross pieces 4, having flanges 4' bolted to the flanges 1' of the I-beams, being clamped between the I-beams by bolts 5 and having bolted thereto the top boards 6. The table has fixed thereto brackets 7 having journaled in bearings 8 thereof a main driving shaft 9 to which power is transmitted from a pulley 10 through a usual form of clutch 11 splined on the shaft. The clutch may be retracted to disengage its teeth 11' from the teeth 10' on the hub of the pulley by means of a lever 12 pivoted on the bracket 13 and having pins 14 disposed in the channel 15 in the clutch sleeve. Sprocket wheels 16 are fixed on the driving shaft 9 and sprocket wheels 17 are fixed on a shaft 18 journaled in bearings 19' of brackets 19 at the opposite end of the table from the brackets 7. Sprocket chains 20, passing over the sprocket wheels 16 and 17 and through slots 6' in the table top, have fixed thereto transverse slats 21 adapted for engaging the edges of blanks, which are carried thereby across the top of the table.

Brackets 22 are bolted to the respective I-beams 1 and support a frame 23 extending across and above the table. A plate 24, fixed to the frame 23 with its lower edge slightly above the surface of the table, forms the front wall of a magazine in which are stacked blanks to which strips are to be applied, the blank at the bottom of the pile being engaged by a slat 21 and carried along the table under the frame upon the operation of the machine. The blanks are aligned so as to have the strip applied to the desired part thereof by a side plate 25 adjustably fixed to an arm 26 by a bolt 27. The arm 26 is pivoted to the frame 23 by a bolt 28 and fixed in position by a bolt 29 fixed to an abutment 23' on the frame and passing through the slot 26' in the arm. The plate 26 may thus be adjusted to accommodate blanks of any size within the capacity of the machine and to provide for the application thereto of the tape strip in the desired lateral position. A paste or water basin 30 is bolted to the frame 23 and has journaled in the sides thereof a roller 31 by which an

adhesive or moistening fluid may be applied to the tape strip. A bracket 32, bolted to the frame 23, supports standards 33 having thereon bearings 34 in which is journaled a 5 spindle 35. Hubs 36 are sleeved on the spindle 35 and have therein spokes 37 forming a reel for a roll of tape. Springs 38, disposed between the bearings 34 and the hubs 36, tend to yieldingly press the latter together 10 so that tape rolls of various widths may be centered and carried by the reel. Tape is fed from the reel through the loop 39, under the bottom and over the vertical face of the bracket 40 which has fingers 41 pivoted thereto by pins 42 and pressed against the vertical face thereof by springs 43 anchored 15 to the knobs 44 on the bracket 32, whereby the tape is held in position.

A frame 45, having bearings 46 through 20 which pass the standards 33 (upon which the frame is adapted to reciprocate), has fixed thereto a knife 47. A double bell crank 48, fulcrumed on the spindle 49 journaled in the frame 45, has pivoted between 25 arms 48' thereof a link 50 pivotally connected through a holder 52 with a knife 53 adapted to reciprocate along guides 54 fixed to the frame 45 and to coöperate with the knife 47. The arms 48' of the bell crank 30 have pivoted between them a link 55 which has its opposite end pinned between the bifurcated end of a bent lever 56. A rod 57, fixed to a bearing 58 pivoted in the frame 45, slides through an aperture in a bearing 35 59 pivoted between the arms 48' of the bell crank, the outward movement of the latter being limited by a pin 60 in the rod. A spring 61 loosely coiled on the rod 57 between the bearings 58 and 59 normally holds 40 the bell crank in position to keep the knife 53 retracted, the spring being strong enough to support the frame and prevent the rocking of the bell crank 48 by the upward movement of the end of the lever 56 except 45 ing when the frame is held against further movement by the stops 62 on the standards 33. The tape is cut by the rocking of the bell crank 48 and the reciprocation of the knife 53 when the frame 45 is in its highest 50 position, thus leaving an end of the tape projecting above the fingers 41 and knife 47 in the lower position of the frame to afford a hold for the gripper mechanism.

A bracket 63 is bolted to an I-beam 1 and 55 has an arm 64 with a hanger 65 depending therefrom. A shaft 66, having a sprocket wheel 67 fixed thereon, is journaled in a bearing 68' of the bracket and extends 60 through a shaft 69 journaled in the bearing 65' of the hanger 65. The sprocket wheel 67 is driven through a chain 71 by a sprocket wheel 72 fixed on the shaft 73 mounted in bearings 74 of the brackets 7. This shaft 65 has fixed thereto a disk 75 and loosely sleeved thereon a cog wheel 76, the cog wheel

being adjustably fixable in relation to the shaft by bolts 77 passing through slots 78 in the cog wheel and through the disk. A pinion 79 fixed on the main driving shaft 9 drives the cog wheel and therethrough the 70 shaft 73.

The shaft 66 has pinned thereto a sleeve 80 having a flange 81 thereon, and also has sleeved thereon a cam 82 having therethrough slots 83. Bolts 84 passing through the 75 flange 81 and slots 83 clamp the sleeve and cam together in desired adjustable relation. The cam 82 acts on a roller 85 on the end of an arm 86 keyed to a shaft 87, journaled in bearings 89 of brackets 90 bolted on the arm 80 64, which it rocks to oscillate the lever 56 on the other end thereof and therethrough operate the cutting mechanism.

A wheel 91 has a hub 92 fixed by a key 93 to the shaft 66 and a hub 94 revolvably 85 mounted on a hollow shaft or tube 95 supported by a bracket 96 bolted to an I-beam 1, the tube 95 being connected with an exhauster or other source of vacuum X. A chamber 96 is formed in the wheel by the 90 flanges 92' and 94' on the hubs and the rim 97 having therein apertures 98, air being exhausted from this chamber through the tube 95 and the suction exerted by the vacuum in the wheel acting through the apertures 98 95 on strips placed on the rim causing such strips to adhere thereto.

The shaft 69 has fixed thereto by a key 99 a radial arm 100 having a plate 101 extending over the rim of the wheel 91. A bell 100 crank 102 has its apex fixed on an arbor 103 journaled in a bearing 100' of the arm 100. The arm 102' of this bell crank has thereon a pin 102a disposed in a slot 104' of a lever 104 which is fixed to a pintle 105 of a gripper jaw 106 journaled in bearings 107 of the plate 101, the pin and slot connection between the arm and lever permitting the rocking of the lever to open the jaw when the bell crank is rocked.

The arm 102'' of the bell crank has pivoted thereto on the pin 108 a bell crank 109. The arm 109' of this bell crank forms a latch normally resting upon the top of a pin 110 on the arm 100 and has therein a notch 115 109a in which the pin is adapted to be engaged when the bell crank 102 is rocked to retract the bell crank 109. A spring 111 anchored to the stud 112 on the arm 100 has its end connected to the arm 109'' of the bell 120 crank 109 through which it acts on the bell crank 102 to close the jaw 106 when the pin 110 is disengaged from the notch 109a, and on the latch 109' to engage the pin in the notch when the bell crank 102 is rocked to 125 open the jaw 106. The bell crank 102 is rocked to open the jaw through a lever 113 fixed on the arbor 103 and having thereon a roller 114 controlled by a cam 115 adjustably bolted to the hub 92 of the wheel 91. 130

The latch 109' is elevated, to disengage the pin 110 from the notch 109^a so that the spring 111 may rock the bell crank 102 and close the jaw 106, by an adjustable bolt 116 in a bracket 117 carried by the hanger 65.

5 The arm 100 is oscillated through a segmental gear 118 fixed on the shaft 69 and having teeth 118' meshing with teeth 119 of a rack 120. The rack 120 is fixed on a shaft 121 mounted in bearings 63" and 65" of the bracket 63 and hanger 65 respectively, the shaft having fixed thereto a crank 122 with a wrist pin 123 extending through a slot 124 of a pitman or connecting rod 125 to which it is adapted to be clamped in adjustable relation by a nut 126.

10 A crank 127 fixed on the shaft 73 has therein a slot 127' in which is disposed the head 128' of a bolt 128 having thereon the nut 128" by which the cam 129 and flanged block 130 are adjustably fixed to the eccentric. The head 125' of the pitman 125 has therein a slot 125^a in which the block 130 is adapted to slide, separation of the head and block being prevented by the flanges on the latter. Rollers 125^b on the head 125' engage the cam 129 wherethrough the pitman is operated, the cam being so shaped that at certain points its rotation around the axis 25 of the shaft 73 is compensated for and no movement is communicated to the pitman.

15 In operation, blanks stacked in the magazine are alined so as to bring the desired section thereof in the plane of the tape strip 35 by suitably adjusting the plate 25, and the blanks fed forward over the top of the table by the slats 21.

20 In the position of the apparatus shown in Fig. 7, the latch 109' having been tilted upon the downward movement of the arm 100 by the screw 116 to disengage the notch 109^a from the pin 110, and the jaw 106 having been closed over the end of the tape projecting above the knife 47 by the action of the 25 spring 111 through the bell cranks 109 and 102 and lever 104, the arm 100 is beginning to be moved upward by the mechanism connecting it with the pitman 125. When the desired length of tape has been drawn by 30 the gripper mechanism over the rim of the wheel 91, as illustrated diagrammatically in Fig. 9, the arm 100 is held stationary, due to the movement of the pitman actuating rollers 125^b on the irregular perimeter of the cam 129 which compensates for the movement of the cam around the axis of the eccentric 127. During this period of rest, the cam 82 rocks the lever 56, through the arm 86 and shaft 87, raising the frame 45 to the 35 limit of its upward movement. The lever 56 being rocked farther by the cam and the further movement of the frame 45 being prevented by the stops 62, the bell crank 48 is thrown against the resistance of the spring 61, whereby the knife 53 is advanced

and in conjunction with the knife 47 cuts the tape, the latter being drawn and held by suction on the rim of the wheel 91. The cam 115 on the hub of the wheel 91 then rocks the lever 113 and, through the arbor 103, throws the bell crank 102 and lever 104 to open the jaw 106 and release the tape, the jaw being held open by the engagement of the latch 109' on the pin 110 through the action of the spring 111. The tape is carried 70 downward by the constantly revolving suction wheel 91 in contact with the roller 31 and applied to a blank A, as shown in Fig. 10, the blank having been carried by a slat 21 into position for receiving it. Upon the 75 throw of the pitman 125 in the reverse direction, the gripper mechanism is again carried downward, being held stationary, due to the cam 129, upon the tripping of the latch 109' while the gripper jaw 160 seizes 80 the tape end left projecting above the knife 47 by the descent of the frame 45.

85 It will be observed that the top surface of the table is entirely clear of obstructions so that blanks of any width, up to that of the 90 table may be used, and strips of desired lengths may be applied at a desired moment in the travel of the blanks by suitably adjusting the relation of the driving shafts 9 and 73 through the cog wheel 76 and disk 95 75; the oscillation and positions of rest of the arm 100 by adjustment of the crank wrist-pin 126 in the pitman slot 124, the block 130 relative to the axis of the crank 127, and the cam 129; the operation of the 100 gripper jaws by adjustment of the cam 115 on the hub 91 and the elevation of the screw 116; and the action of the cutting mechanism by adjustment of the cam 82 relative to the shaft 66.

105 It will be understood that by "tape" is meant a strip of any suitable material.

Having described my invention, I claim:

1. In a machine of the character described, movable mechanical gripper mechanism 110 adapted for automatically engaging and drawing therewith a fabric, frictional mechanism adapted for restraining the movement of said fabric, means for cutting said fabric into sections, means for operating said cutting mechanism and gripping mechanism in synchronous relation, and a movable suction device for engaging said fabric and translating said sections.

2. In a machine of the character described, 120 means for holding a fabric by the application of pressure thereto, automatically acting mechanism for gripping said fabric and drawing it from said means, a revoluble suction wheel to which said gripper mechanism 125 draws said fabric, and a reciprocating cutting mechanism movable relatively to said holding means for cutting said fabric into sections.

3. In a machine of the character described, 130

- holding means for frictionally engaging a fabric, an oscillating gripper mechanism adapted for engaging said fabric and drawing it through said holding means, means comprising a revoluble device adapted for pneumatically holding said fabric, a cutter movable toward and from said holding means, and means for operating said cutter when withdrawn from said holding means
- 10 to sever said fabric.
4. In a machine of the character described, a revoluble suction wheel, a tape holder, means for drawing tape from said holder over said wheel oppositely to its direction of 15 rotation and delivering said tape to said wheel, and means for severing the section of said tape delivered to said wheel.
5. In a machine of the character described, a holder adapted for applying pressure to 20 tape drawn therethrough, a suction device, and oscillating gripper mechanism for carrying tape from said holder to said device.
6. In a machine of the character described, a tape holder, a suction wheel, oscillating 25 gripper mechanism for carrying tape from said holder to said wheel, and mechanism for cutting said tape between said holder and carrying mechanism.
7. In a machine of the character described, 30 a blank magazine, a conveyer for carrying a blank from said magazine, a tape holder having means for restraining the movement of tape drawn therethrough, oscillating gripper mechanism for drawing tape from said holder, a reciprocating knife for cutting said tape, and a wheel for pressing said tape against a blank carried by said conveyer.
8. In a machine of the character described, 35 a blank magazine, a conveyer for carrying blanks from said magazine, a tape holder having gripping means, oscillating gripper mechanism for drawing tape from said holder, and a suction wheel to which tape is carried by said gripper mechanism and by which said tape is pressed upon a blank carried by said conveyer.
9. In a machine of the character described, 40 a blank carrier, a tape holder having gripping means, a suction device, oscillating gripper mechanism for drawing said tape from said holder to said device, and means for rendering said tape adhesive, said tape being carried by said suction device to a blank on said carrier.
10. In apparatus of the character described, 45 a tape holder, strip applying mechanism comprising a carrier, gripper mechanism comprising a jaw movable about an axis and over the surface of said carrier, said gripper mechanism drawing tape from said holder to said carrier, a lever connected with said jaw, means comprising a cam for operating said lever, and means for applying suction to tape on said carrier.
11. In apparatus of the character described, a tape holder, gripper mechanism movable about an axis and comprising a jaw, means comprising a lever and cam for opening said jaw, means comprising a latch whereby said jaw is maintained in open position, and means for releasing said latch and permitting said jaw to grip tape carried by said holder.
12. In apparatus of the character described, 50 a revoluble suction wheel, gripper mechanism having a common axis with said wheel and traveling over the rim thereof, and means for operating said gripper mechanism.
13. In apparatus of the character described, a revoluble shaft, a suction wheel thereon, an oscillating gripper mechanism movable about an axis and comprising a jaw adapted for carrying a strip to said wheel, means comprising a spring normally holding said jaw in one position, and means comprising a cam for moving said jaw from said first named position.
14. In apparatus of the character described, 55 reciprocating gripper mechanism comprising an oscillating arm, a jaw carried thereby, a lever connected with said jaw, a bell crank connected with said lever, a latch connected with said bell crank, and means in the path of said latch for tilting it.
15. In apparatus of the character described, 60 an oscillating arm, a jaw pivoted thereto, a lever connected with said jaw, a bell crank connected with said lever and having a spindle journaled in said arm, a second bell crank having a latch for locking said first named bell crank, a spring connected with said second named bell crank, and means for releasing said latch.
16. In apparatus of the character described, 65 a tape holder, a reciprocating carriage, cutting mechanism carried thereby, means for operating said cutting mechanism in one position of said carriage, gripper mechanism, a journaled device to which said gripper mechanism carries tape from said holder past said knife, and means for operating said gripper mechanism in another position of said carriage.
17. In apparatus of the character described, 70 a tape holder, a suction wheel gripper mechanism for drawing tape from said holder to said wheel, mechanism for cutting tape drawn by said gripper mechanism, and means for operating said last named mechanism comprising a pitman, an eccentric, and a cam through which said eccentric operates said pitman.
18. In apparatus of the character described, 75 a tape holder, oscillating gripper mechanism for drawing intermittently desired lengths of tape from said holder, and tape applying means for receiving said tape length from said gripper mechanism, in 80

combination with a blank conveyer, a driving shaft, means connecting said conveyer and driving shaft, means connecting said tape applying means and driving shaft, and 5 means for adjusting the relation between said conveyer and tape applying means so that a tape strip carried thereby may be applied to various parts of a blank on said conveyer.

10 19. In apparatus of the character described, a tape holder, a suction wheel, oscillating mechanical gripper mechanism movable about the axis of said wheel for drawing tape from said holder to said wheel, and 15 a traveling conveyer adapted for carrying a blank into position for receiving tape from said wheel.

20 20. In apparatus of the character described, cutting mechanism, a revoluble shaft, a suction wheel fixed on said shaft, gripper mechanism sleeved on said shaft, a cam revolved by said shaft for operating said cutting mechanism, and a cam revolved by said shaft for operating said gripper 25 mechanism.

21. In apparatus of the character described, the combination of a tape carrier, means comprising jaws for holding an end of tape carried by said carrier, mechanism for gripping said tape, a cutter for severing 30 said tape, means for rendering said tape adhesive, and a device for carrying said tape in contact with said means last named.

22. In apparatus of the character described, the combination of a tape carrier, 35 means for severing tape carried by said carrier, means comprising oscillating gripper mechanism having a movable jaw for engaging said tape, means for rendering said tape adhesive, and means comprising a vacuum 40 member against which the tape is atmospherically pressed for delivering said tape.

In witness whereof I have hereunto set my name this 7th day of August, 1912, in the presence of the subscribing witnesses.

RALPH E. BATES.
